US0D1049693S

(12) **United States Design Patent** (10) **Patent No.:** **US D1,049,693 S**
(45) **Date of Patent:** **** Nov. 5, 2024**

(54) **RAZOR HANGER**

(71) Applicant: **The Gillette Company LLC**, Boston, MA (US)

(72) Inventors: **Jonathon Albert Riehle**, Brighton, MA (US); **Armando Miguel Hurtado**, Boston, MA (US)

(73) Assignee: **The Gillette Company LLC**, Boston, MA (US)

(**) Term: **15 Years**

(21) Appl. No.: **29/862,659**

(22) Filed: **Dec. 12, 2022**

Related U.S. Application Data

(62) Division of application No. 29/741,900, filed on Jul. 16, 2020, now Pat. No. Des. 976,610.

CLAIM

The ornamental design for a razor hanger as shown and described.

DESCRIPTION

FIG. 1 is a front perspective view of a design of a razor hanger of the present invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

(Continued)

The dash broken lines show portions of the razor hanger that form no part of the claimed design.

1 Claim, 5 Drawing Sheets
